[57] CLAIM

The ornamental design for a food container, as shown and described.

DESCRIPTION

FIG. 1 is a perspective view of a food container showing our new design;

FIG. 2 is a top plan view thereof;

FIG. 3 is a front elevation thereof, the rear elevation being a mirror image thereof;

FIG. 4 is a left side elevation thereof, the right side elevation being a mirror image thereof;

FIG. 5 is a bottom plan view thereof;

FIG. 6 is a perspective view of another embodiment of FIG. 1;

FIG. 7 is a top plan view of FIG. 6;

FIG. 8 is a bottom plan view of FIG. 6;

FIG. 9 is a rear elevation of FIG. 6;

FIG. 10 is a left side elevation of FIG. 6;

FIG. 11 is a front elevation of FIG. 6; and

FIG. 12 is a right side elevation of FIG. 6.
